UNITED STATES PATENT OFFICE

2,048,485

WEB PRINTING ROTARY PRESS

Howard M. Barber, Pawcatuck, Conn., assignor
to C. B. Cottrell & Sons Company, Westerly,
R. I., a corporation of Delaware

Application July 27, 1935, Serial No. 33,497

3 Claims. (Cl. 101—178)

In high speed rotary web printing presses where quick drying inks and a web heating and cooling unit is employed, it is very desirable that the printing and web heating and cooling units be so located with respect to each other as to produce the best results while occupying a minimum amount of space.

My invention comprises, generally, a printing unit located at one end of the press, a combined heating and cooling unit located at the opposite end of the press, and a web supply roll, all located in line with the press, the printing unit comprising an impression cylinder and a plurality of form cylinders (five in the present instance) arranged around the same, and the combined heating and cooling unit comprising a large heating cylinder and two small cooling cylinders located between the heating cylinder and the impression cylinder.

My invention more particularly comprises an arrangement of the above character in which three form cylinders are arranged upon one side of the impression cylinder and two form cylinders upon the other side thereof.

Practical embodiments of my invention are represented in the accompanying drawings, in which,

Fig. 1 represents a diagrammatic side elevation of one form of my invention;

Fig. 2 represents a similar view of another form of my invention; and

Fig. 3 represents a similar view of a third form of my invention.

The printing unit which is located at one end of the press is herein represented as a five color unit, the impression cylinder being denoted by 1 and the two form cylinders on one side of the impression cylinder by 2, 3, and the three form cylinders upon the other side of the impression cylinder by 4, 5, 6.

The inking mechanisms for the form cylinders are denoted by 2a, 3a, 4a, 5a, 6a.

The combined heating and cooling unit which is located at the opposite end of the press is herein represented as comprising a large heating cylinder 7 and two small cooling cylinders 8, 9, said cooling cylinders being located between the printing unit and the heating cylinder of the combined heating and cooling unit. This combined heating and cooling unit is located in line with the press.

The web supply roll is denoted by 10 and it also is located in line with the press.

In the form illustrated in Fig. 1 the web is led from the supply roll 10, which is located below

both the printing unit and the combined heating and cooling unit and beyond the printing unit, to and through the printing unit and from thence to and through the combined heating and cooling unit. In this form the web is delivered at the 5 end of the press opposite to that occupied by the web supply roll and in a path passing under the heating and cooling unit.

In the form illustrated in Fig. 2 the web is led from the supply roll 10 which, in this instance, is 10 also located below the printing and combined heating and cooling units and at the opposite end of the press from the printing unit, to and through the printing unit and from thence to and through the combined heating and cooling unit. 15 In this form the web is delivered at the same end of the press as that in which the web supply roll is located and in a path passing under the heating and cooling unit.

In the form shown in Fig. 3 the web supply 20 roll is located below and at the opposite end of the press from the printing unit and the said heating and cooling unit is located above the printing unit. In this form the web is led to and through the printing unit and from thence to and 25 through the combined heating and cooling unit. From thence the web is delivered at the same end of the press as that occupied by the web supply roll and in a path passing under the heating and cooling unit.

It will be understood that guide rolls are provided for passing the web in the prescribed paths from the web supply roll 10 to the delivery.

It will also be understood that any suitable heating medium, such as steam, may be supplied 35 to the heating cylinder 7 and that any suitable cooling medium, such as water, may be supplied to the cooling cylinders 8, 9.

It will also be understood that any well known or approved quick drying inks may be used in the 40 printing unit.

What I claim is:

1. In a multicolor rotary printing press, a printing unit located at one end of the press, a combined heating and cooling unit located at the 45 opposite end of the press and a web supply roll, all located in line with the press, and means for leading the web through the printing and combined heating and cooling units and delivering the web at the opposite end of the press from the 50 printing unit, the said printing unit comprising an impression cylinder and five form cylinders arranged around the same.

2. In a multicolor rotary printing press, a printing unit located at one end of the press, a 55

- combined heating and cooling unit located at the opposite end of the press and a web supply roll, all located in line with the press, and means for leading the web through the printing and combined heating and cooling units and delivering the web at the opposite end of the press from the printing unit, the said printing unit comprising an impression cylinder and five form cylinders arranged around the same, two form cylinders upon one side and three form cylinders upon the other side of the impression cylinder.
3. In a multicolor rotary printing press, a printing unit located at one end of the press, a combined heating and cooling unit located at the

opposite end of the press, and a web supply roll, all located in line with the press, the combined heating and cooling unit being located above the printing unit and the web supply roll being located below the printing unit, and means for leading the web through the printing and combined heating and cooling units and delivering the web in a path passing under the heating and cooling unit at the end of the press where the web supply roll is located, the said printing unit comprising an impression cylinder and five form cylinders arranged around the same. 5 10

HOWARD M. BARBER.
